UNITED STATES PATENT OFFICE.

ADOLPH P. SCHNYDER, OF POAG, ILLINOIS.

WELL-EXCAVATING APPARATUS.

Application filed December 4, 1926. Serial No. 152,551.

This invention relates to well excavating apparatus and has for its objects the provision of an apparatus which is of compact construction so that it can be used in the excavating of wells of comparatively small diameters and which is flexibly suspended by cables from a derrick located above the mouth of the well so that said apparatus may be used in the excavating of wells of various depths.

Further objects of my invention are to mount the excavating member or bucket so that it may reach the bottom of the well in inverted position and can then be actuated to right itself whereupon the entering edge of said bucket digs itself into the ground and fills said bucket.

Still further objects of the invention are to provide a suitable cable suspension for said excavating member and a separate cable connection for actuating said excavating member from its inverted position, said cable connection being utilized in hoisting the filled excavating member and in holding said member in upright position.

Other objects of the invention are to provide a suitable framework for supporting and guiding the excavating member and provided with suitable tackle gear for operatively connecting thereto the hoisting and operating cables.

Additional objects of the invention are to provide a well excavating apparatus of a simple construction which can be easily operated by means of cables and which is so constructed that fine sand as well as mud can be excavated by means of said cables.

With these and other objects in view, my invention consists in certain novel features of construction and arrangement of parts, hereinafter more fully described and claimed, and illustrated in the accompanying drawings, in which—

Figure 1 is a vertical cross section through the lower end of a well with the apparatus located therein and the excavating member occupying inverted position.

Figure 2 is a similar view but showing the excavating member in upright position.

Figure 3 is a horizontal cross section taken on lines 3—3 of Figure 1.

Figure 4 is a view similar to Figure 1 but

showing the excavating apparatus in front elevation.

Figure 5 is a horizontal cross section taken on lines 5—5 of Figure 2.

Figure 6 is a detail view taken on lines 6—6 of Figure 4, with the sheaves removed therefrom.

Figure 7 is a front elevational view of the hoisting machine, utilized for operating the cables.

Figure 8 is a vertical cross section through a well showing the modified form of excavating apparatus wherein two excavating members are used.

Figure 9 is a fragmental view showing the excavating members in partly moved position.

My present invention relates more particularly to well excavating apparatus and is particularly designed for use in sinking well casings of the type such as described in my Patent No. 1,038,973. In this type of wells the well casings are formed in sections which are sunk into the ground in superimposed relation while the ground within the well is removed therefrom.

Briefly stated my excavating apparatus includes a bucket or excavating member of suitable dimensions to allow the admission thereof into the well casing. A cable suspension is provided for lowering and raising said bucket, the latter being pivotally mounted on said suspension means and being overbalanced so that when released it will occupy inverted position with its cutting edge presented downwardly. A cable connection is used to right the bucket when the latter is resting on the bottom of the well whereby the bucket upon being operated on its pivots digs into the ground and fills itself. The filled bucket is then hoisted from the well and is emptied.

Referring by numerals to the accompanying drawings, 10 indicates a section of a well casing provided at its lower end with a cutting end 10^a. Suspended within the casing by means of a cable 11 is a framework 12 on which is supported a tackle apparatus or power transmission mechanism 13 comprising a moving block 14 and a standing block 15. The framework comprises a vertically disposed channel member 16 to the upper

end of which is fixed one end of cable 11 as indicated at 11^a. A pair of vertically disposed plates 17 are fixed to the flanges 16^a of member 16 near the upper end thereof and are provided with bearings 18 in which is journaled a shaft 19 for carrying a pair of sheaves 20 of standing block 15. A horizontally extending member 21 is fixed to the lower end of channel member 16 by means 10 of rivets 22. A series of brackets 24 are fixed to member 21 and extend therefrom to receive rollers 25 which latter are spaced equi-distant from each other. These rollers are adapted to engage the inner periphery 15 of casing 10 and guide framework 12 during its travel therethrough. Extending downwardly from member 21 is a pair of arms 26 to the lower ends of which is pivotally connected by pins 27 an excavating 20 member or bucket 28. Pivotal members 27 are located near the bottom of bucket 28 so that the latter will have a tendency to occupy inverted position.

Bucket 28 is preferably semi-spherical 25 in shape having a curved bottom 29 and having its sides partly formed straight as indicated at 30. The entering edge of the bucket is provided with pointed teeth as indicated at 31 to facilitate the digging operation of the bucket. Projecting from each side 30 beyond the open end of the bucket is an arm 32 to which is pivotally connected one end of a link 34, the opposite end of the latter being pivotally connected to the lower end of an arm 35, the upper of 30 which is pivotally mounted on a shaft 36 of a moving block 14. The pivotally interconnected ends of links 34 and arms 35 are spaced from each other by a spacer 38 and the pivotally interconnected ends of links 34 and arms 32 are spaced from each other by a bar 39, the latter being formed preferably triangular in cross section with the apex presented away from bucket 29.

Moving block 14 consists of a series of 45 sheaves 40 which are carried by shaft 36. A cable 41 having one end fixed to channel member 11 as indicated at 42 passes downwardly over one of the sheaves 40 of block 50 14 and then upwardly over one of the sheaves 20 of block 15 then downwardly again over the next sheaf 40 and then upwardly over the second sheaf 20 and the free end of the cable then extends upwardly 55 through the well as indicated at 44 and is operatively connected to a drum 45 of a hoisting machine 46, while the free end of cable 11 is operatively connected to a second drum 47 of hoisting machine 46 as shown in Figure 7. Drums 45 and 47 may be operated independently of each other or in conjunction as desired so that both cables 11 and 44 may be used in hoisting the apparatus after the bucket 28 has been moved in upright position.

In the operation of my excavating apparatus the tackle 13 is lowered through the casing 10 with the bucket 28 occupying inverted positions as shown in Figures 1 and 4. Upon reaching the bottom of the well 50 cable 44 is operated thereby causing moving block 14 to be moved towards block 15. This movement exerts pull on arms 35 which in turn operate links 34. Links 34 bear against the edge of bucket 28 at points disposed opposite to entering edge 31 which is forced into the ground. In doing so the bucket becomes filled with the loosened material. The upward movement of block 14 brings bucket 28 into position shown in Figure 2. In this 80 position arms 32 are presented upwardly and are in alignment with links 34 and arms 35. After bucket 28 has been actuated to occupy upright positions, cable 11 is operated to hoist the bucket from the well so as 85 to remove the contents thereof. In raising the bucket 28 cable 44 may be utilized to assist in this operation thereby insuring against slack in cable 44 and the consequent 90 accidental displacement of said bucket and the spilling of the material contained therein. Arms 32 are disposed to one side of the axis of bucket 28 while pivots 27 are disposed on the opposite side of the central line 95 of bucket 28 so that when tension on the cable 44 is released bucket 28 will have a tendency to rock on its pivots and occupy inverted position.

In traversing the casing 10 the apparatus is maintained in proper spaced relation 100 by means of guide rollers 25 which are arranged so as to prevent the framework 12 or parts thereof coming in contact with the well casing; said rollers also maintain the bucket in proper central position. Normally a certain amount of clearance exists between rollers 25 and the inner periphery of 105 casing 10 as shown in Figure 3 in order to allow certain amount of play for the apparatus and bucket 28, particularly when 110 the latter is being actuated at the bottom of the well.

In Figures 8 and 9 a modified form of excavating apparatus is shown. This form is 115 particularly adapted for use on the surface, as in loading and unloading sand and similar material, and the like, and consists of two excavating buckets 28^a carried by a framework 47, the latter comprising vertically disposed channel members 48 spaced 120 from each other and carrying at their lower ends 49, by means of arms 26^a rigidly connected thereto, said bucket 28^a. The upper ends of channel members 48 are connected together by a pair of plates 50 in which are 125 mounted block and tackle mechanism 13^a for actuating said members 28^a. A pair of pulleys 51 is mounted on plates 50 in spaced relation with block and tackle mechanism 13^a and cables 52 after operating over the 130

sheaves 20* and 40* pass inwardly under pulleys 51 and then upwardly toward the hoisting machine. Said cables 52 can be operated independently of each other, or they 5 may be united together as indicated at 53 a suitable distance from pulleys 51 so that both cables 52 are operated simultaneously at a uniform speed. A cable 54 is preferably connected to each channel member 48 and 10 serves to hoist the framework 47.

The block and tackle gear of my improved apparatus serves as a speed reducing means for operating the bucket and provides the power necessary to actuate the bucket when 15 the latter is engaged in digging or loosening the soil or material it is desired to remove. Any number of sheaves 20 and 40 can be used to obtain the necessary power. Cable 11 forms a flexible suspension for 20 lowering and raising the framework 12 and the excavating member carried thereby. In this manner a well of any depth can be dug by the use of my improved novel excavating apparatus.

25 My invention is primarily intended for use in excavating wells. However, it is equally as applicable for use in hoisting material such as sand and the like.

While I have shown and described the 30 preferred embodiment of my invention, it is obvious that various changes in the construction and arrangement of parts can be made and substituted for those herein shown and described without departing from the 35 spirit of my invention.

I claim:

1. An excavating apparatus comprising a supporting framework, flexible suspension means therefor, an excavating and material 40 holding bucket pivotally mounted on said framework, block and tackle mechanism on said framework and connected to said bucket for actuating the latter on its pivots, and cable connections for operating said 45 block and tackle mechanism.

2. An excavating apparatus comprising a supporting framework, flexible suspension means therefor, an excavating and material holding bucket pivotally mounted on said framework, block and tackle mechanism on said framework and connected to said bucket for actuating the latter on its pivots, cable connections for operating said block and tackle mechanism, and hoisting 55 means for operating said flexible suspension means.

3. An excavating apparatus comprising a supporting framework, flexible suspension means therefor, an excavating and material 60 holding bucket pivotally mounted on said framework, block and tackle mechanism on said framework and connected to said bucket for actuating the latter on its pivots, cable connections for operating said block and tackle mechanism, and hoisting 65 means

for simultaneously or independently operating said flexible suspension means and said cable connections.

4. An excavating apparatus comprising a supporting framework adapted to enter a well, a cable for hoisting said framework, an excavating bucket pivotally mounted on said framework, a power transmission mechanism comprising interconnected revolute members supported by said framework, articulated connections between said power transmission mechanism and said bucket for actuating the latter, and cable connections for actuating said block and tackle mechanism. 75

5. An excavating apparatus comprising a supporting framework adapted to enter a well, a cable for hoisting said framework, an excavating bucket pivotally mounted on said framework, a block and tackle mechanism supported by said framework, articulated connections between said block and tackle mechanism and said bucket for actuating the latter, cable connections for actuating said block and tackle mechanism, and guide 80 means on said framework for guiding it during its travel in the well.

6. An excavating apparatus comprising a supporting framework adapted to enter a well, a cable for hoisting said framework, an excavating bucket pivotally mounted on said framework, a power transmission mechanism supported by said framework including cooperating revolute members, articulated connections between said power transmission mechanism and said bucket for actuating the latter, cable connections for actuating said power transmission mechanism, brackets extending laterally from said framework, and guide rollers journaled in said 95 brackets and adapted to engage the face of the well for guiding said framework therethrough and maintaining it in proper position therein. 100

7. An excavating apparatus comprising a supporting framework, a pair of depending arms fixed to the lower end of said framework, an excavating and material holding bucket pivotally mounted on the lower ends of said arms, a block and tackle mechanism supported by the upper end of said framework, articulated connections pivotally connected to said block and tackle mechanism and to said bucket whereby the actuation of said block and tackle mechanism operates said bucket on its pivotal supports and causes inversion or upright positioning of said bucket, cable connections for operating said block and tackle mechanism and extending upwardly therefrom to the mouth of the well, and cable connections for hoisting said framework and parts supported thereby. 115

8. An excavating apparatus comprising a supporting framework, a pair of depending arms fixed to the lower end of said frame- 125

- work, an excavating and material holding bucket pivotally mounted on the lower ends of said arms, a block and tackle mechanism supported by the upper end of said framework, articulated connections pivotally connected to said block and tackle mechanism and to said bucket whereby the actuation of said block and tackle mechanism operates said bucket on its pivotal supports and causes inversion or upright positioning of said bucket, cable connections for operating said block and tackle mechanism and extending upwardly therefrom to the mouth of the well, cable connections for hoisting said framework and parts supported thereby, and guide rollers mounted on said framework adapted to guide said bucket and spaced from said framework for guiding the latter during its travel through the well.
- 10 15 20 25 30 35 40 45 50 55 60 65 70 75 80 85 90 95 100 105 110 115 120 125 130
16. An excavating apparatus comprising a supporting framework, a pair of depending arms fixed to the lower end of said framework, an excavating and material holding bucket pivotally mounted on the lower ends of said arms, a block and tackle mechanism supported by the upper end of said framework, articulated connections pivotally connected to said block and tackle mechanism and to said bucket whereby the actuation of said block and tackle mechanism operates said bucket on its pivotal supports and causes inversion or upright positioning of said bucket, cable connections for operating said block and tackle mechanism and extending upwardly therefrom to the mouth of the well, cable connections for hoisting said framework and parts supported thereby, and a hoisting machine for operating said cables.
17. In a well excavating apparatus, a framework, a one-piece invertible material cutting and holding member pivotally mounted on the framework, a speed reducing device for actuating said member on its pivots at reduced speed, and guide rollers carried by said framework for guiding the apparatus during the travel thereof through the well.
18. In a well excavating apparatus, a framework adapted to enter a well, a single piece material cutting and holding member pivotally mounted on said framework, the pivotal points of said member being arranged near the bottom thereof and to one side of the vertical axis of same and block and tackle means for actuating said member on said pivots, said means having pivotal operative connection with said member near the top thereof and on the opposite side of the vertical axis of same.
19. An excavating apparatus comprising in combination a framework, a suspension cable attached to said framework for lowering and hoisting the same, a single piece material cutting and holding member pivotally mounted on the lower end of said framework, the pivotal points being arranged near the bottom of said member and to one side of the vertical axis thereof, block and tackle mechanism supported by said framework above said material holding member, linkage connections between said block and tackle mechanism and said material holding member and having a pivotal connection with the latter near the top thereof and on the opposite side of the vertical axis of same, and means for actuating said block and tackle mechanism.
20. An excavating apparatus comprising in combination a framework, a suspension cable attached to said framework for lowering and hoisting the same, a single piece material cutting and holding member pivotally mounted on the lower end of said framework, the pivotal points being arranged near the bottom of said member and to one side of the vertical axis thereof, block and tackle mechanism supported by said framework about said material holding member, linkage connections between said block and tackle mechanism and said material holding member and having a pivotal connection with the latter near the top thereof and on the opposite side of the vertical axis of same, means for actuating said block and tackle mechanism, and guide rollers carried by said framework and arranged in spaced relation therewith for guiding the apparatus during its travel in a well.
21. An excavating apparatus comprising in combination a framework, a suspension cable secured to the upper end of said framework, an invertible single piece material cutting and holding member pivotally mounted on the lower end of said framework, a standing block supported on the upper end of said framework, a moving block arranged below said standing block, a cable having one end fixed to said framework and operating over said blocks and having its opposite end extending upwardly, and linkage connections pivotally connected to said moving block and to said material holding member whereby the latter is operated on its pivots by means of said last-mentioned cable.
22. In a well excavating apparatus, the combination of a framework, a suspension cable fixed at one end to said framework, a hoisting machine for receiving the other end of said suspension cable, a block and tackle mechanism supported on said framework including a cable having one end fixed to said framework and the other end operatively connected to said hoisting machine, a single piece material and cutting and holding member pivotally mounted on the lower end of said framework, the pivotal points being disposed to one side of said material holding member to allow inversion thereof,

and articulated connections pivotally connected at their upper end to said block and tackle mechanism and at their lower end to said material holding member for operating the latter from its inverted position, the pivotal connection between said material holding member and said linkage connections being disposed at points spaced in a

definite relation with the pivots of said material holding member to allow inversion 10 thereof when said block and tackle mechanism is released.

In testimony whereof I hereunto affix my signature this 24th day of November, 1926.

ADOLPH P. SCHNYDER.
